PLOW

James Morkoski, Canton, Ill., assignor to International Harvester Company, a corporation of New Jersey

Application April 12, 1940, Serial No. 329,338.

20 Claims. (Cl. 97—100)

The present invention relates to gang plows, and more particularly to a bracing means for the rear ends of the beams that carry the earth-working tools.

5 It is desirable in gang plows to maintain all of the earth-working tools in a rigid position with respect to one another, so as to plow furrows of a uniform depth. It has been the practice to bolt a tie bar to the rear ends of the plow beams to hold the earth-working tools in a rigid position. This arrangement has been unsatisfactory since the pull of the earth-working tools on the tie bar would cause the bar to bend. It has also been found that the weight of the earth-working tools 10 would sag the tie bar when the plow was in a transport position.

15 It is, therefore, an object of the present invention to provide a bracing means for the tie bar of a plow.

20 Another object of the invention is to provide an adjustable bracing means which will prevent the tie bar from sagging.

25 Another object of the invention is to provide an adjustable bracing means on one side of a bar which will counteract stresses applied to the other side of the bar.

30 According to the present invention adjustable compression members are provided on the tie bar of the plow. These members can be adjusted so that the tie bar can be arched.

35 These and other objects and advantages of the present invention will be apparent to those skilled in the art after a consideration of the following detailed description of the invention, taken in conjunction with the accompanying drawings, in which:

Figure 1 is a plan view of a gang plow frame with the novel bracing means provided on the tie bar;

40 Figure 2 is a rear view of the gang plow taken at a right angle to the tie bar;

Figure 3 is a sectional view of the bracing means on the tie bar, taken along the line 3—3 of Figure 1;

45 Figure 4 is a sectional view taken along the line 4—4 of Figure 1;

Figure 5 is a plan view of a gang plow frame with a modified bracing means for the tie bar;

50 Figure 6 is a rear view of the gang plow taken at a right angle to the tie bar;

Figure 7 is a perspective view of another form of bracing means for the tie bar; and,

55 Figure 8 is a rear view taken along the line 8—8 of Figure 5.

Referring to Figure 1, there is shown a gang

plow frame 10 which consists of a plurality of longitudinally arranged plow beams 11 connected together at their front ends by a transverse bar 12. The conventional wheel supports 13, 14, and 15 and power lift 16 are shown in dotted lines. 5 Brace members 17 are provided between the beams 11. At the rear end of the beams 11 is bolted a curved beam 11a which has an earth-working tool or plow bottom 18 secured thereto.

On each of the curved beams 11a is secured a bracket member 19 with which is associated a tie bar 20. The brackets 19 are provided with openings 21.

A series of parts, 22 having openings 23 provided therein are associated with the brackets 19. 15 Bolts 24 are inserted in the openings 21 in the brackets 19 and the openings 23 in the parts 22. Nuts 25 are provided on each of the bolts 24 which, when tightened, secure the tie bar 20 to the brackets 19. 20

Each of the parts 22 has a projection 26 in which there is provided an opening 27. The openings 27 are parallel to, and spaced from the tie bar 20. Rods 28 having threaded end portions 29 are inserted in the openings 27. Nuts 30 25 are provided on the threaded ends 29 of the rods 28. As shown in Figures 1 and 4, the tie bar 20 is held against fore and aft movement with respect to the brackets 19 by bolts 31 which are provided at opposite ends of the tie bar 20. 30

Referring to Figure 2, the plow bottoms are shown on the ground line x. In order that the nuts 30 on the rods 28 may be adjusted a block a is provided under the center plow bottom. The ground line is now at y. The weight of the plow 35 bottoms on each side of the center plow bottom pulls the ends of the bar downwardly. The nuts 30 on the rod 28 above the center plow bottom are then tightened against the sides of the parts 22. The nuts 30 are tightened on the rods 28a, then 40 the nuts 30 on the rods 28b, then the nuts on the rods 28c, and then the nuts 30 on the rods 28d. The rods 28d are tightened against the parts 22 which contact the bolts 31. By tightening the nuts on the rods 28, 28a, 28b, 28c, and 28d, the 45 tie bar is held in its arched position. When the rods are all in compression, the block a is then removed, and the plow is supported on the wheels 13, 14, and 15. When the plow is in a transport position the weight of the plow bottoms on the tie 50 bar 20 will pull the bar down into an approximately straight line position. When the plow is in an operating position the pull on the plow bottoms pulls the tie bar into an approximately straight line position. Should the tie bar at any time sag, 55

the tie bar can be arched to a greater degree by adjusting the nuts 30 on the rods in the manner just described.

Another form of bracing means is shown in Figures 5 and 7. In Figure 5, the plow frame 10 consists of longitudinally arranged plow beams 11 connected together at their front ends by a transverse bar 12. Brace members 17 are provided between the beams 11. At the rear end of the beams 11 is bolted a curved beam 11a which has an earth-working tool or plow bottom 18 secured thereto.

On each of the curved beams 11a is secured an L-shaped bracket 19a having a series of holes 15 provided therein. A tie bar 32 is associated with the top side of each of the L-shaped brackets, as shown in Figure 8. A series of plate members 33 and 33a having openings provided therein are placed on top of the bar 32. Bolts 34 are inserted 20 in the openings in the bracket 19a and the openings in the plate members 33 and 33a. Nuts 34a are provided on each of the bolts 34 which, when tightened, secure the bar 32 to the brackets 19a.

The bracing means in this case comprises a 25 pair of rods 35, the ends of which are welded to the plate members 33a. A vertical plate 36, having socket members 37 welded thereto, is welded to the plate members 33. The ends of the rods 35 have threaded end portions on which nuts 38 30 are provided. The threaded ends of the rods 35 are inserted in the socket members 37.

The adjustment of the bracing means in this case is accomplished by also placing a block *a* under the center plow bottom. The weight of the 35 plow bottoms will sag the ends of the beam downwardly so that the nuts 38 may be tightened against the sockets 37.

Another form of bracing means is shown in Figure 7. In this case the ends of a bar 35a are 40 welded to the plate members 33a. The center of the bar 35a is welded to a vertical plate 36a which is in turn welded to the plate members 33. A bar 39 is also welded to the plate members 33. The ends of the bar 39 extend under the members 33a.

The adjustment of this bracing means is also 45 accomplished by placing a block *a* under the center plow bottom. The weight of the plow bottoms 18 on each side of the center plow bottom pulls the ends of the bar 32 downwardly. The bolts 34 extending through the plate members 33 and 33a are then tightened.

By virtue of the present invention, the longitudinally arranged beams are rigidly connected so as to form a frame. A bar is associated with the rear ends of the beam, and is provided with a bracing means which reinforces the bar. The weight of the plow bottoms on the bar, which heretofore deflected the bar when the plow is in a transport position is now prevented by the bracing means, and the pull of the plow bottoms on the bar which heretofore sagged the bar when the plow is in an operating position is also prevented by the bracing means. The adjustment of the bracing means holds the plow bottoms in a level 60 position at all times.

It is the intention to limit the invention only within the spirit and scope of the appended claims.

70 What is claimed is:

1. In a plow, a plurality of longitudinally extending beams having depending portions at their rear ends adapted to have plow bottoms fixed thereto, draft means connected to the forward ends of said beams, a bar extending across

the rear ends of said beams, means for clamping said bar to said beams, adjustable members spaced from said bar, means for connecting said members at spaced points to said bar, and means for adjusting said members against their points of connection whereby said members are placed in compression. 6

2. In a plow, at least three longitudinally extending beams having depending portions at their rear ends adapted to have plow bottoms 10 fixed thereto, draft means connected to the forward ends of said beams, a bar extending across the rear ends of said beams, means for clamping said bar to said beams, adjustable members 15 spaced from said bar, means for connecting said members at spaced points to said bar, and means for adjusting said members against their connection to the beam to maintain the plow bottoms in the same plane.

3. In a plow, a plurality of longitudinally extending beams having depending portions at their rear ends adapted to have plow bottoms fixed thereto, draft means connected to the forward ends of said beams, a bar extending diagonally across the rear ends of said beams, means 20 for clamping said bar to said beams, a plurality of adjustable members spaced from said bar, means on said bar adapted to receive said adjustable members, and means for adjusting said adjustable members against said means, whereby said adjustable members are placed in compression to resist movement of the bar in the direction of said adjustable members. 25

4. In a plow, a plurality of longitudinally extending beams having depending portions at their rear ends adapted to have plow bottoms 30 fixed thereto, means connecting the forward ends of said beams, a bar extending diagonally across the rear ends of said beams, means for clamping said bar to said beams to form a rigid frame, adjustable members spaced from said bar, means for connecting said adjustable members to said bar, and means for adjusting said adjustable members against its connections to said bar, 35 whereby said adjustable members are placed in compression to resist movement of said bar in the direction of said adjustable members. 40

5. In a plow, a plurality of spaced beams, means connecting the front ends of said beams, 50 downwardly extending portions fixed to the rear ends of the beams, earth working means connected to said downwardly extending portions, a diagonal bar associated with the rear ends of said beams, means for securing said bar to said beams, rods spaced from said bar, adjustable means on the ends of said rods, brackets on said bar adapted to receive the ends of said rods, and means for adjusting said adjustable means on said rods against said brackets to apply a force 55 against said bar in one direction to counteract the force applied to said bar by said earth working means in the other direction.

6. In a plow, a plurality of spaced beams, means connecting the front ends of said beams, 65 earth working means fixed to the rear ends of the beams, a bar associated with the rear ends of said beams, means for securing said bar to said beams, rods associated with said bar, adjustable means on the ends of said rods, brackets 70 on said bar adapted to receive the ends of said rods, means for adjusting said adjustable means against said brackets to apply a force to said bar in one direction to counteract forces applied to said bar in the other direction. 75

7. In a plow, a plurality of spaced beams having depending portions at their rear ends adapted to have plow bottoms fixed thereto, draft means connected to the forward ends of said beams, a bar extending across the rear ends of said beams, means for clamping said bar to said beams, adjustable members secured at spaced points on said bar, and means for adjusting said members to apply a force on said bar in one direction to counteract the force applied by said plow bottoms to said bar in the other direction.

8. In a plow, a plurality of longitudinally extending beams having depending portions at their rear ends adapted to have plow bottoms fixed thereto, means connecting the forward ends of said beams, means connecting the rear ends of said beams comprising a bracket fixed to the rear end of each beam, a bar clamped to said brackets, and an adjustable member disposed between said clamps and adjustable against said clamps to apply pressure against said clamps to counteract the pressure of said beams against said bar.

9. In a plow, a plurality of longitudinally extending beams having depending portions at their rear ends adapted to have plow bottoms fixed thereto, means connecting the forward ends of said beams, a bracket fixed at the rear ends of said beams, a bar associated with said brackets, means for clamping said bar to said brackets, and adjustable members spaced from said bar and disposed between and adjustable against said last mentioned means, whereby the adjustable members counteract the forces applied to said bar by said plow bottoms.

10. In a plow, a plurality of longitudinally extending beams having depending portions at their rear ends adapted to have plow bottoms fixed thereto, means connecting the forward ends of said beams, a bracket fixed at the rear ends of said beams, a bar associated with said brackets, a part for each bracket associated with said bar, means for clamping said parts and said bar to said brackets, and adjustable members disposed between said parts and adjustable against said parts.

11. In a plow, a plurality of longitudinally extending beams having depending portions at their rear ends adapted to have plow bottoms fixed thereto, means connecting the forward ends of said beams, brackets respectively fixed at the rear ends of said beams, a bar associated with said brackets, parts associated with said bar and clamped to said brackets, and adjustable members spaced from said bar and disposed between said parts and adjustable against said parts.

12. In combination, a plurality of spaced plow beams having downwardly depending portions at their rear ends adapted to have plow bottoms fixed thereto, bracket members secured to the rear ends of the beams, a tie bar associated with said bracket members, parts having openings associated with said tie bar, means for securing said parts and said tie bar to said bracket members, rods having threaded end portions inserted in the openings in said part, and nuts on the threaded portions of the rods adjustable into contact with the sides of said parts to exert downward stress on the tie bar.

13. In combination, a plurality of spaced plow beams having downwardly depending portions at their rear ends adapted to have plow bottoms fixed thereto, means connecting the front ends of the beams, a tie bar connected to the rear ends of said beams, projections having openings

therein extending upwardly from said tie bar, rods having threaded end portions inserted in the openings in said projections, and nuts on said threaded portions of said rods adjustable against said projections to exert a force along said bar.

14. In combination, a plurality of spaced plow beams having downwardly depending portions adapted to have plow bottoms fixed thereto, means connecting the forward ends of said beams, brackets having a recess formed therein secured to the ends of said beams, a tie bar adapted to fit the recess in each bracket, clamps adapted to fit the tie bar, means for securing said clamps and said tie bar to said brackets, said clamps having a portion extending therefrom provided with openings, rods having threaded end portions inserted in said openings, nuts on the threaded portions of said rods adjustable against the portion of said clamp, and means on the tie bar contacting the first and last brackets to hold said tie bar from moving relative to said brackets.

15. In a plow, a plurality of spaced plow beams having downwardly depending portions at their rear ends adapted to have plow bottoms fixed thereto, draft means connected to the front ends of the beams, a tie bar associated with the rear ends of said beams, means for clamping said tie bar to said beams, means for holding said tie bar from moving relative to said beams, adjustable means spaced from and connected to said tie bar at spaced points, and means for adjusting said adjustable means against said means for holding the tie bar from moving relative to said beams.

16. In a plow, a plurality of longitudinally extending plow beams having downwardly depending portions at their rear ends adapted to have plow bottoms fixed thereto, draft means connected to the front ends of the beams, a bar associated with the rear ends of said beams, means for clamping said bar to said beams, a pair of rods secured near the ends of said bar, a bracket secured near the center of said bar, said rods extending toward one another and associated with said center bracket, and means on said rods adjustable against said center bracket, whereby a force is applied against the ends of said bar.

17. In a plow, a plurality of longitudinally extending plow beams having downwardly depending portions at their rear ends adapted to have plow bottoms fixed thereto, draft means connected to the front ends of the beams, L-shaped brackets secured to the rear ends of said beams, a bar associated with said brackets, means for securing said bar to said brackets, adjustable members secured to two brackets, a projection extending from a bracket intermediate said two brackets, said adjustable members associated with said intermediate bracket, and means on said rods adjustable against said intermediate bracket to exert a force against the ends of said bar.

18. In a plow, a plurality of longitudinally extending beams having depending portions at their rear ends adapted to have plow bottoms fixed thereto, draft means connected to the forward ends of said beams, a bar extending across the rear ends of said beams, means for clamping said bar to said beams, means for holding said bar from moving relative to said beams, adjustable members spaced from said bar, means for connecting said members at spaced points to said bar, and means for adjusting said members

against their points of connection whereby said members are placed in compression.

19. In a plow, a plurality of longitudinally extending beams having depending portions at their rear ends adapted to have plow bottoms fixed thereto, means connecting the forward ends of said beams, means connecting the rear ends of said beams comprising a bracket fixed to the rear end of each beam, a bar clamped to said brackets, means for holding said bar from moving relative to said brackets, and an adjustable member disposed between said clamps and adjustable against said clamps to apply pressure against said clamps to counteract the pressure of said beams against said bar.

20. In a plow, a plurality of spaced beams having depending portions at their rear ends adapted to have plow bottoms fixed thereto, draft means connected to the forward ends of said beams, a bar extending across the rear ends of said beams, means for clamping said bar to said beams, means for holding said bar from moving relative to said beams, adjustable members secured at spaced points on said bar, and means for adjusting said members to apply a force on said bar in one direction to counteract the force applied by said plow bottoms to said bar in the other directions.

JAMES MORKOSKI.
